UNITED STATES PATENT OFFICE.

ABNER E. SHEPHERDSON, OF MELROSE, MASSACHUSETTS.

ARCHER'S BOW.

1,396,788.

Specification of Letters Patent. Patented Nov. 15, 1921.

Application filed May 9, 1918. Serial No. 233,428.

To all whom it may concern:

Be it known that I, ABNER E. SHEPHERDSON, a citizen of the United States, residing at Melrose, county of Middlesex, State of 5 Massachusetts, have invented an Improvement in Archers' Bows, of which the following description, in connection with the accompanying drawing, is a specification, like characters on the drawing representing like

10 parts.

This invention relates to bows such as archers use, and particularly to bows of the jointed type in which the limbs are separable from each other and detachably secured to 15 together.

The object of the invention is to provide a novel jointed bow having wooden limbs which has superior casting qualities, which is constructed so that it is rigid and un 20 yielding at the handle portion thereof, and which has other advantages, all as will be more fully hereinafter set forth.

In order to give an understanding of the invention, I have illustrated in the drawings a selected embodiment of the invention which will now be described, after which the 25 novel features thereof will be pointed out in the appended claims.

Figure 1 is a view of an archer's bow embodying my invention;

Fig. 2 is an enlarged section through the handle portion of the bow;

Fig. 3 is a side view of the handle showing parts in section to better show the 35 construction;

Fig. 4 is a section on the line 4—4, Fig. 2; Fig. 5 shows the bow disjointed.

As stated above, my bow is of the type in which the upper and lower limbs are separable from each other and detachably secured together. These limbs are made of wood, and the manner in which they are connected together is such as to produce at the central or handle portion of the bow a rigid, 40 unyielding section of a length substantially the same as the width of a person's hand, and also so as to produce at such central portion an increased weight which is of assistance in steadyng the bow when it is released.

In the bow illustrated in the drawings, 1 indicates the upper limb, 2 the lower limb, and 3 the string. The limbs are both made of wood and are connected by the handle portion 4, one or both of the limbs being de-

tachably secured to the handle as desired. The detachable connection between the handle and the limb is provided for by making the handle with a socket into which the inner end of the removable or separable limb 60 is received. Where both limbs are detachable from the handle, then the latter will have a socket in each end thereof and this is the construction herein illustrated.

The handle member herein shown is in 65 the form of a stiff, cylindrical shell 4 preferably of metal which is open at both ends and is provided with a suitable covering to give a good feeling in the hand. Any suitable material may be used for covering the 70 shell 4, but I find good results are secured by winding the shell with a strip of tape 5 and then applying to the outside of the tape an exterior envelop 6 of leather or suitable material, the exterior envelop being united to 75 the tape by glue or other cementitious substance.

Each limb of the bow is provided at its inner end with a metal ferrule 7 which accurately fits the interior of the shell 4. Each 80 ferrule 7 is preferably made somewhat longer than one-half the length of the shell 4 so that when the ferruled ends of the two limbs are inserted into the ends of the shell sufficiently so that they meet, as shown in Fig. 85 2, the outer ends of the ferrules 7 will project slightly beyond the ends of the shell. In fitting the ferrule 7 to the limb ends I will preferably turn the limb ends down thereby to form the shoulder 8 on each limb against 90 which the end of the ferrule abuts, the portion 9 of the limb immediately beyond the end of the ferrule having a diameter equal to that of the ferrule. A second ferrule or ring 10 is then slipped over the first ferrule 95 7 and positioned so as to embrace both the outer end of the ferrule 7 and the portion 9 of the bow limb adjacent the ferrule 7. This band or ring 10 acts to confine the wood fibers immediately adjacent the end of the 100 ferrule 7 and thus prevents any tendency of the wood to split at this point.

Each end of the shell-like handle 4 thus constitutes a socket to removably receive the ferruled end of a bow limb.

For properly positioning the limbs 1 and 2 in the handle, I propose to employ interlocking means between each bow member and the handle. Such interlocking means can conveniently be in the form of a posi- 110

tioning pin or projection 11 extending from the bow limb and adapted to enter a notch 12 formed in the edge of the handle or shell

4. This interlocking connection permits the 5 bow limb to be readily removed from the handle and at the same time holds it from turning in the handle after it has been reinserted therein.

With this construction either or both 10 limbs may be removed from the handle when the bow is not in use, thus shortening by one-half the space occupied by the bow, as seen in Fig. 5. This is a decided advantage because the ordinary archer's bow used by men 15 is six feet long, and any article of this length is more or less awkward to carry or transport. An article having a length of only about three feet, however, is relatively easy to carry around.

20 There is another advantage which results from the construction herein shown, and that is that the bow is rendered stiff and unyielding at the central portion. Neither the metallic handle 4 nor the ferrules 7 will give 25 or bend when the bow is drawn and hence all of the bend in the bow must take place beyond the ferrules 7. This results in increasing the cast of the bow because a bow which bends in the handle as well as in the 30 limbs when it is drawn has less casting power than a bow which bends in the limbs only.

There is a still further advantage resulting 35 from the above construction and that is that the presence of the metallic handle 4 and ferrules 7 increase slightly the weight at the handle, and the result is to increase the smoothness with which the bow projects the arrow and to decrease the tendency of the bow to kick when the string is released. I 40 attribute this to the fact that the inertia of the added weight at the handle tends to steady the bow and to overcome any tendency to kick.

In nocking the arrow it is the practice to 45 rest the arrow on the side of the bow directly above the handle, said arrow being held in this position while the bow is being drawn and when it is released.

In the construction herein shown the band 50 or ring 10 is situated at a slight distance from the end of the handle 4 and the space between the band or ring and handle constitutes an arrow-guiding groove which receives the arrow while the bow is being drawn and 55 when it is released.

While I have herein illustrated a construction in which both limbs are detachable from the handle, yet the advantages above enumerated could be secured if one limb only were 60 detachable from the handle and the other limb were permanently secured thereto.

Another advantage resulting from the sectional bow is that if either limb becomes accidentally broken, it can readily be replaced 65 with a new limb, thus making a new bow

and obviating the necessity of discarding the entire bow.

I claim:

1. In an archer's bow, the combination with a rigid, tubular handle portion of metal 70 provided with a notch at each end, of two wooden limbs, each having a metal ferrule at its inner end which fits into one end of said tubular handle portion, each ferrule being slightly longer than one-half the 75 length of the handle portion so that when the limbs are placed in the handle portion with their ends abutting, the ferrules project beyond the handle portion, and a pin extending through each ferrule and into the 80 wooden limb and having a portion projecting beyond said ferrule to engage one of said notches, said pins operating both to assist in retaining the ferrule on the limb and to insure the proper position of each limb in 85 the handle and relative to each other, said handle portion and ferrule providing a rigid, unyielding central portion to the bow and also providing additional weight at the handle portion which increases the steadiness 90 of the bow when the string is released.

2. In an archer's bow, the combination with a rigid, tubular handle portion having a length approximately the same as the width of the hand, of two limbs each having at its inner end a metal ferrule of uniform diameter throughout its length which tightly fits into one end of said handle portion, each ferrule being slightly longer than one-half the length of the handle portion 100 so that when the limbs are set into the handle the ferrules project beyond the ends of the handle, the portion of each limb which is inclosed by the ferrule being of slightly reduced diameter so that the exterior of the 105 ferrule is flush with the exterior of the limb adjacent the end of the ferrule, and a band encircling the projecting end of each ferrule and the portion of the limb adjacent said ferrule end, said bands eliminating any 110 tendency of the wooden limb to check at the end of the ferrule due to the bending of the limb as the bow is drawn and the band on the upper limb being properly spaced from the end of the handle to form between it 115 and the handle an arrow-guiding groove.

3. In an archer's bow, the combination with a rigid, tubular handle portion, of two wooden limbs, each having at its inner end a metal ferrule which fits tightly into the 120 tubular handle, each ferrule having a length slightly greater than one-half the length of the handle whereby the two ferrules project slightly beyond the ends of the handle, and a band encircling the projecting end of each 125 ferrule and the portion of the limb immediately adjacent said end, said band forming between itself and the end of the handle an arrow-guiding groove.

4. In an archer's bow, the combination 130

with a rigid, tubular handle portion of metal, of two solid wooden limbs each having its inner end inclosed by a ferrule which is open at both ends and which is slightly longer than one-half the length of the handle, each ferrule being of a size to tightly fit into the tubular handle, the end of each ferrule being flush with the end of the corresponding limb whereby when the limbs are inserted into the handle with their ends meeting a wood-to-wood contact is provided, coöperating means on the ferrules and handles to position the limbs properly relative to each other when they are inserted into the handle, the handle portion and the ferrules providing sufficient additional weight at the handle portion of the bow so as to steady the bow when the string is released. 15

In testimony whereof, I have signed my name to this specification.

ABNER E. SHEPHERDSON.
